UNITED STATES PATENT OFFICE.

HARRY D. HEUER, OF ST. LOUIS, MISSOURI.

STREET-TRAFFIC-SIGNAL APPARATUS.

1,264,300.

Specification of Letters Patent. Patented Apr. 30, 1918.

Application filed May 23, 1914. Serial No. 940,604.

To all whom it may concern:

Be it known that I, HARRY D. HEUER, a citizen of the United States, and resident of St. Louis, Missouri, have invented certain 5 new and useful Improvements in Street-Traffic-Signal Apparatus, of which the following is a specification containing a full, clear, and exact description, reference being had to the accompanying drawings, forming a part hereof.

My invention relates to improvements in street traffic signal apparatuses, and the object of my invention is to construct a simple and inexpensive apparatus comprising a 15 signal device arranged to be suspended from a suitable hanger overhead a street crossing where it will be visible from all directions for some considerable distance, and to arrange a simple means for operating the 20 signal device from the surface at a point preferably removed from the intersection of the median lines of the crossing streets, where the traffic guardian is removed from the danger incident to traffic, and where a 25 shelter may be stationed for the protection and comfort of the traffic guardian.

With the above purposes in view, my invention consists of certain novel features of construction which will be fully set forth 30 in the following specification, pointed out in my claims, and illustrated in the accompanying drawings, in which—

Figure 1 shows in plan my improved traffic signal apparatus as in use at a street crossing;

Fig. 2 is an elevation of the apparatus as shown in Fig. 1;

Fig. 3 shows in plan the rotatable signal device, a portion of its hanger and the rods 40 and chain for rotating it;

Fig. 4 is a diagrammatical elevation of the signal device and its operating means;

Fig. 5 is a vertical sectional elevation showing the pivoted support for the semaphores and the electrical connections for the lamps carried by the semaphores;

Fig. 6 is a sectional plan taken on the line 6—6 of Fig. 5;

Fig. 7 shows in plan the lever for operating the semaphore; and

Fig. 8 is a sectional plan taken on the line 8—8 of Fig. 4, showing the direction

pulleys carried by one of the supporting posts.

Referring by numerals to the accompanying drawings:

10—10 designates posts which are preferably placed at diagonally opposite corners of a street crossing, as shown in Fig. 1. Strung between these posts from points near 60 their tops is a cable 11, and intermediate the ends of the cable is a hanger 12, which is in a position overhead the intersecting point of the median lines of the crossed streets.

Suspended from the hanger 12 is a bell 13, in which is rotatably mounted a shaft 14 carrying at its lower end a hub 15 provided with the radially arranged pockets, each of which pockets is designed for the support 70 of a semaphore. There are preferably four of the semaphores, two of which are of one color and the other two of a contrasting color. The semaphores 16—16 are preferably colored red on both faces, and the 75 semaphores 17—17 colored white on both faces.

Secured to the shaft 14 which carries the semaphores is a sprocket wheel 18, and secured to one of the posts 10 in approximate 80 horizontal alinement with the sprocket wheel 18 is a pair of direction pulleys 19. The base for the post carrying the direction pulleys is preferably a glazed shelter house such as 20, of sufficient size to comfortably 85 house the traffic guardian and the semaphore operating mechanism.

Arranged within the shelter house and preferably secured to the wall thereof, as shown in Fig. 7, is a bearing 21, in which 90 is rotatably mounted a shaft 22 supporting a sprocket wheel 23, vertically alining with the post 10, and an operating lever 24.

Riding upon the sprocket wheel 18 connected with the semaphores and the sprocket 95 wheel 23 within the shelter house are the sprocket chain sections 25 and 26, and riding over the direction pulleys 19 are the chain sections 27—27.

Extended upwardly through the shelter 100 house and the post 10 is a pair of rods 28, which connect the ends of the sprocket chain section 26 with the one end of each of the chain sections 27—27, the other ends of the

chain sections 27—27 being connected with the ends of the chain section 25 by the rods 29—29.

By the arrangement and construction of 5 the parts just described I have provided a signal apparatus which will be visible from all directions for a considerable distance, even though there be a congestion of traffic in the immediate vicinity of the signal device, and have provided a signal operating 10 means on the surface, located out of the path of traffic where a shelter house may be located.

The traffic guardian from within the shelter house may control traffic by rocking the 15 lever 24, which through the various rods, chains, and sprocket wheels revolves the signal device, showing the "red" or "stop" semaphores to traffic in both directions on 20 one street, and the "white" or "clear" semaphores in both directions to the traffic on the other street.

In order that the signals may be effective 25 at night, I arrange lamps on the semaphores. In the drawings I have shown incandescent electric lamps arranged in pairs on each face of the semaphores, the "red" semaphores 16 carrying "red" lamps 30 and the "white" semaphores 17 carrying "white" 30 lamps 31.

In order that only one color of lamp be shown from any one direction, I provide the shades 32 which project laterally from each face of each semaphore outside of the lamps.

35 The shaft 14 is formed hollow for a portion of its length, and the wires leading from the lamps occupy this hollow portion of the shaft. At the upper end of this hollow portion of the shaft the wires lead 40 to a pair of contacts 33, insulated from the shaft, but rotatable therewith. Arranged to successively engage the contacts 33 is a brush 34 secured to the fixed bell 13, and leading from the brush 34 is a feed wire 35. 45 Arranged diametrically opposite the brush 34 is a second brush 36 to engage the contacts 33 when moved, and leading from the brush 36 is a feed wire 37 in which is located a switch 38, which switch provides 50 means for turning the lights on and off, as occasion demands.

In order to provide an audible signal coincident with the movement of the semaphores, I arrange an electric bell 39 preferably on the post 10 over the shelter house, and wire the bell in a circuit including a battery 40, a pair of contacts 41—41 located adjacent the path of travel of the lever 24, and the lever itself. So that each time the 60 traffic guardian moves the lever 24 to change the position of the semaphores, the lever 24 engaging the contacts 41—41 completes the electric circuit, including the bell 39.

When the signal apparatus of my inven-

tion is not in use as a guide to traffic, the 65 semaphores may be placed diagonally and by rearrangement this disposition of the semaphores will indicate the absence of a guardian and put traffic under its own control. 70

Having thus described my invention, what I claim as new therein and desire to secure by Letters Patent of the United States therefor, is:

1. A street traffic signal apparatus comprising supports positioned on opposite sides of the street, a cable connected to said supports, a semaphore support secured intermediate of the ends of said cable, a rotatable semaphore mounted on said support, a lamp carried by said semaphore, an operating lever positioned adjacent to one of the cable carrying supports, a flexible connection between said lever and semaphore, an electric circuit, and a circuit closing and 85 breaking means in the path of movement of said lever and said semaphore.

2. A street traffic signal apparatus comprising supports positioned on opposite sides of a street crossing, a cable connected 90 to said supports, a semaphore support secured intermediate of the ends of said cable and positioned above street traffic, a rotatable semaphore mounted on said support, said semaphore comprising a series of four 95 blades, a lamp carried by each blade, a shade carried by each blade, an operating lever positioned adjacent to one of the cable carrying supports, a flexible connection between said lever and semaphore, an electric 100 circuit, and a circuit closing and breaking means in the path of the movement of said lever and semaphore.

3. A street traffic signal apparatus comprising supports positioned on opposite 105 sides of a street crossing, a cable connected to said supports, a semaphore support secured intermediate of the ends of said cable and positioned substantially above the intersection of the streets, a rotatable semaphore mounted on said support, an incandescent electric lamp carried by said semaphore, an electric circuit for said lamp provided with contact terminals, an operating lever positioned adjacent to one of the cable 110 carrying supports, a flexible connection between said lever and semaphore, an electric circuit, and contact terminals carried by the 115 semaphore support.

4. A street traffic signal apparatus comprising supports positioned on opposite sides of a street, a suspended cable connected to said supports, a semaphore hanger secured and suspended from said cable, electric contact terminals carried by said 120 hanger, electric circuit wires leading to said contacts, a shaft revolvably mounted in said hanger, electric circuit terminals rotatably 125

carried by the said shaft, semaphore blades carried by said shaft, electric lamp circuits for each blade, a hand operating lever positioned adjacent to one of the cable carrying supports, and a flexible connection between said lever and semaphore.

5 In testimony whereof, I have signed my

name to this specification, in presence of two subscribing witnesses.

HARRY D. HEUER.
